UNITED STATES PATENT OFFICE.

LOUIS ANTOINE GACHEY, OF PARIS, FRANCE.

DEVICE FOR THE EVACUATION OF WASTE SCRAPS FROM KITCHENS OR THE LIKE.

Application filed August 2, 1927, Serial No. 210,129, and in France August 6, 1926.

This invention has for its object the provision of evacuating devices for dealing with waste scraps from kitchens by means of a fixture over the sink operated by a flushing of water and the reception of the scraps thus diverted into draining boxes placed under ground.

With this object each kitchen is provided with a sink-drainer placed under the water tap, which is prevented from overflowing by a waste preventing device and the liquid sealing of which is assured by means of a siphon; furthermore the sink-drainer is provided at its base with a plug or obturating valve that is operated when the scraps are to be ejected.

The annexed drawings shew, by way of example two methods of carrying the invention into effect.

In the drawings:—

Fig. 1 is a longitudinal section of one form of sink-drainer made according to the invention.

Fig. 2 shews an elevation of a special key for operating the obturating valve.

Fig. 3 is a longitudinal section shewing a variation in the sink-drainer.

The sink-drainer shewn in Fig. 1 comprises a sink of stone, enamelled cast iron or other suitable material, *a*, placed under the kitchen tap, which receives the washing water used for the hands, vegetables, and crockery, etc. . . . and comprising at its central part a removable sieve or plate *b* of aluminium or other suitable material, provided with apertures *c* for the passage of water and its reception in a truncated conical body *d* which supports the sink *a*. The base of the body *d* is fixed to a cone *e* seated and sealed in the floor.

The upper part of the body *d* of the drainer is provided with a calibrated covering in two parts, *f*, *f'*, the lower part *f'* of which is fixed by its edge to the body *d* whilst the upper part or central piece *f* is carried by a three armed support *g*, itself fixed to the body *d*.

In the support *g* and the piece *f* is disposed, in such a way as to enable it to slide therein, a waste or overflow pipe *h* pierced at its upper part with orifices or openings *h'* which permit the passage of the water to the interior of the pipe *h*. This water flows to a double cup-siphon *i*, the plate of which supports a plug or obturating valve *j* and is perforated with draining holes *i'*. The valve or plug *j* which is fixed to the central pipe *h* includes in

its interior the cup-siphon *i* and is furnished on the exterior with an india rubber ring *k* resting on a fixed seating *l*.

In Fig. 2 is shewn a key *m* with projections permitting the upper plate *b* easily to be raised for its removal, allowing the tube *h* together with its obturating plug *j* to be raised.

Method of operation.—The body *d* of the sink-drainer containing a certain quantity of water due to culinary operations, has passed thereinto according to their production the household scraps which are sent to the down-fall pipe and from there to the receiving apparatus in the following manner. The cover *b* is raised and the scraps are thrown on to the calibrated cover. Those which are of small enough dimensions pass freely through the cover and fall to the bottom, collecting above the plug *j*, the scraps which are too large, which have been stopped above the disc *f* are withdrawn and reduced by any desired means to dimensions sufficiently small so that they can pass between the parts *f* and *f'*. They can then fall to the lower part of the apparatus. To evacuate the scraps accumulated above the plug *j* the key *m* is introduced into the upper part of the tube *h* where it catches in one of the holes *h'* and the whole is raised; that is to say the plug *j* opens or uncovers the lower end or orifice of the body *d* of the drainer. The scraps which are drawn down by the water in the apparatus fall through the cone *e* to the down-fall pipe *n* which opens above a receiving apparatus.

Fig. 3 shews in vertical section a varied form of sink-drainer to that shewn in Fig. 1.

In this simplified construction the body *d'* is extended into a seating cone *d''* for the obturating plug *j'*.

The calibrated cover in two pieces *f''*, *f'''* and the support *g* of Fig. 1 is replaced by a calibrated cover *b'* having holes *c'* formed in a single piece *f''*, constituted by a plate of special form suspended by three arms *f''* which are supported from a shaped ledge in the central orifice of the sink *a'*.

The cup-siphon carried by the valve *j'* is constituted simply by a single cup suspended by the valve into which the waste or overflow pipe *h''* dips. The removable key *m* Fig. 1 is replaced by a button or head *m'* having two arms forming a T and fixed to come at the upper end of the pipe *h''* *k'* is a packing ring.

The method of operation of the sink drainer as modified is similar to that of the apparatus described with respect to Fig. 1.

What I claim and desire to secure by Letters Patent of the United States of America is:—

1. A device for the evacuation of the waste scraps from kitchen directly by sink-drainers comprising: a sink body with a rim, a truncated conical body supporting the body of the sink and receiving the water coming from the latter; a calibrated cover in two superposed parts; a movable plate covering the open bottom of the body of the sink; holes for the passage of water in this plate; a central movable waste pipe guided at its upper part in a support for the calibrated covering; openings at the upper part of this pipe, an obturating plug fixed at the base of the waste pipe; a tight packing disposed at the exterior of the plug; a truncated conical seating for the obturating plug; a seated cone placed under the base of the drainer; and a discharge pipe into which opens the seated cones.
2. A device for the evacuation of waste scraps from kitchens directly by sink drainers comprising; a sink body with a rim; a lower truncated conical body supporting the body of the sink and receiving the water coming from the latter; a movable plate covering the open bottom of the body of the sink; holes for the passage of water in this plate; a calibrated cover disposed underneath the plate, a central conical part of this cover being fixed by arms to the lower truncated conical body; another annular truncated conical part of the cover disposed in a contrary direction to the first, placed at a certain distance underneath the latter; a movable central waste pipe guided at its upper part in the support of the calibrated cover; openings at the upper part of this pipe; an obturating valve fixed to the base of the waste pipe, a tight packing disposed at the exterior of the valve; a truncated conical seating for the obturating plug, a seated cone placed under the base of the drainer; a double cup-siphon disposed in the interior of the plug and into which dips the base of the waste pipe; openings in the base of the plug for the evacuation of waste; and a dis-

charge pipe into which open all the seated cones.

3. A device for the evacuation of waste scraps from kitchens directly by sink-drainers comprising: a sink body with a rim; a lower truncated conical body supporting the body of the sink and receiving the water coming from this latter, a central metallic cover to direct the scraps in the truncated conical body; a movable plate covering the open bottom of the body of the sink; holes for the passage of water in this plate; a central movable waste pipe overflow openings at the upper part of this pipe; an obturating valve fixed to the base of this waste pipe; a tight packing disposed at the exterior of the valve, a seat for the obturating valve formed at the base of the truncated conical body, a seated conduit placed under the base of the drainer; a bowl or cup with a siphon disposed in the interior of the plug and into which dips the base of the waste pipe, and a discharge pipe.

4. The combination with a kitchen sink having an opening in its bottom, a hollow supporting base registering with the opening, a removable drain cover for the opening, a valve closing the lower end of said base, a valve stem constituting a hollow overflow pipe and means in the valve to water-seal the stem.

5. The combination with a kitchen sink having an opening in its bottom, a hollow truncated body registering with said opening beneath the sink, a drain cover for the opening, means in said body below the sink to permit the passage of larger particles of kitchen waste into said body after removing the cover, a hollow valve at the lower end of said body, an overflow pipe forming the stem of the valve extending proximate to said cover, a water seal in the valve into which the lower end of said pipe dips, said seal discharging water through the bottom of said valve, whereby water overflowing through said stem and water seal will discharge through the bottom of the valve when the valve is closed, and kitchen refuse will discharge past said valve when the stem is lifted.

In witness whereof I affix my signature.

LOUIS ANTOINE GARCHEY.
